UNITED STATES PATENT OFFICE.

WILLIAM J. MAHONEY, OF AMENIA, NEW YORK.

DEVICE FOR CASTING BORDERS, SLUGS, LEADS, AND THE LIKE.

1,169,554.

Specification of Letters Patent.

Patented Jan. 25, 1916.

Application filed March 24, 1915. Serial No. 16,799.

To all whom it may concern:

Be it known that I, WILLIAM J. MAHONEY, a citizen of the United States of America, and a resident of Amenia, in the county of 5 Dutchess and State of New York, have invented a certain new and useful Device for Casting Borders, Slugs, Leads, and the like, of which the following is a specification, the same being a full, clear, and exact description 10 of the invention, such as will enable others skilled in the art to which it appertains to make and use the same.

This invention relates to line casting or matrix setting apparatus such as are ordinarily known as linotype machines, and in particular to an improvement in the vise employed in the same, whereby the latter is adapted to serve as a matrix slide block and to contain a matrix slide.

20 It has been the custom in machines of this general character to assemble the matrices between the jaws of the vise, which are constructed and arranged to register with the mouth of the mold, in order to cast lines of 25 type, and to use in connection therewith supplemental apparatus comprising an independent type casting machine, as a linotype made without the assembling and distributing mechanism thereof, for the purpose of 30 casting borders, leads, rules and slugs. By the use of my invention, however, the line casting machine itself, in complete form, may be adapted to perform all these functions, in addition to the casting of the line, 35 and it may thus not only be utilized for the casting, as separate operations, of type line faces and for the object of the provision of a lead and slug matrix, but also for other purposes, as for example, by the employment 40 of my permanent slide block located in the vise, the casting of dash lines at the end of paragraphs or articles may be done—without having to insert them by hand—conjointly with the use of the apparatus as a 45 matrix setting device.

A machine of the class named equipped with my invention is therefore not only more economical and convenient than those heretofore used, but it is also more rapid, easier 50 to operate and also more efficient in practical use.

With these objects and other purposes in view, the invention consists in the construction, arrangement and operation of parts 55 hereinafter set forth.

In the drawings which accompany and

form a part of this invention, and illustrative of one embodiment of the same, Figure 1 represents a front elevation of a device, constructed according to my invention; Fig. 60 2 is an end elevation of the same; Fig. 2^a is a view in detail of my key; Fig. 3 is an elevation of a slide block in which my invention is embodied; Fig. 3^a is an end view of the same; Fig. 4 is a plan view and Fig. 5 an 65 elevation of another slide block made according to my invention; and Fig. 5^a is an end view of the latter.

Like letters of reference indicate like parts 70 in all the views.

Referring particularly to the drawings, A denotes the left hand half of a vise having a wedge shaped or tapered longitudinally disposed slot or groove a formed in the face of the same and preferably terminating in a 75 rectangular end portion a', serving as a stop. The body of the matrix slide, as B, is ordinarily made with tapered edges to register with, and to enter, the slot a, and preferably has at its inner end a rectangular shoulder b' to engage and register and coöperate with the rectangular part or stop a'. The slide B is preferably rigidly held within the slot a by means of a wedge shaped plate or key D which is ordinarily engaged with a 80 recess formed in the end of the vise, and is made with an orifice through which the screw E, having a knurled head, is entered, which screw engages a threaded orifice in 85 the vise.

A lock nut F, located between the plate 90 D and the head of the screw E, serves to hold the parts securely together. In order to remove one slide B and substitute another one, the screw E and nut F are loosened, 95 whereupon the plate or key D will swing around and hang down on the screw, thereby passing away from the mouth of the slot a, on account of the smallness of the diameter of the upper portion thereof, as 100 shown in dotted lines in Fig. 2. The larger faces of the slides B may be provided, as at a², with characters of any description, or with a suitable design for border slugs, etc., which design will register with the 105 mouth of the mold in the usual manner when the slugs are cast, on which occasions the jaws of the vise are closed.

In instances where it is desired to cast low shoulder dashes, low slugs and leads, a matrix slide C, having a stop C², may be used 110 with the vise A, in connection with a low

faced mold G. The matrix slide C also preferably has an extension C' projecting therefrom which will enter the mouth of the mold, and it is ordinarily formed with an elongated portion C² to overlap the other half of the closed vise, thus serving to prevent any squirting of the metal therebetween during casting operations.

By the use of the structure disclosed here-
10 in, on account of the matrix slide being in-
serted at the outer end or face of the vise
jaw and being securely held in a locked po-
sition, without danger of displacement from
jars or blows incident to the operation of
15 the machine, no open spaces or cracks will
be formed in which the molten metal could
run, as all of the parts are assembled so
closely together as to present a closed sur-
face at the junction of the vise jaw and the
20 matrix slide, the body of the slide C being
flush with the edge portion or meeting face
of the jaw. In casting low shoulder dashes,
low slugs, etc., the use of the matrix slide
C has an especial advantage inasmuch as
25 the extension C' projects from the side face
of the vise in an outward direction and
registers with the face of the mold, the con-
tracted part of the body and the slide lying
under the projection C' being designated in
30 the drawings by the reference character C³.
The projecting face portion C' of the slide C
is extended laterally, as at C², still farther
so as to overlap the sides and joint of the
closed jaws of the vise when in casting po-
35 sition, the said extension C² serving both to
overlap, and also for the purpose of being
supported by, the other or inner jaw A',
and also to close the interstice between the
two jaws which are locked up tight in the
40 casting operation, whereby there is no
chance of the molten metal flowing out at
that point.

I wish it to be understood that I do not
desire to be limited to the exact details of
45 construction shown and described, for ob-
vious modifications will occur to persons
skilled in the art.

What I claim as my invention is:—

1. In a device of the class described, a vise
50 jaw having an undercut groove located in
the same and running longitudinally thereof
to receive a matrix block and being open

at the end distant from the vise jaw, and
contracted adjacent to the jaw, and a ma-
trix slide to register with the said groove 55
and having a shoulder to engage the said
contracted portion to form a closure at the
inner end of the jaw flush with the face of
the same, in combination with means to
close the outer end of the groove and to hold 60
the said slide in operative relation.

2. In a device of the class described, a
vise jaw having an undercut groove located
in the same and running longitudinally there-
of to receive a matrix block and contracted 65
adjacent to the jaw thereof to form a rec-
tangular recess, and a matrix slide to regis-
ter with the undercut portion of the groove
and having means comprising a rectangular
end portion to engage the said contracted 70
portion to form a closure for, and flush with,
the inner end of the jaw.

3. In a device of the class described, a
vise having a groove located in the same
and running longitudinally thereof to re-
ceive a matrix block, and a matrix slide to
register with the said groove, in combina- 75
tion with means to detachably lock the said
slide in the vise comprising a screw to en-
gage the vise, a key adapted to swing on the 80
screw, and a nut to hold the key in opera-
tive position.

4. In a device of the class described, a
vise jaw having an undercut groove located
in the same running longitudinally thereof
to receive a matrix block and being contract- 85
ed adjacent to the jaw meeting face to form
a recess, and a matrix slide to register with
the said groove, the said slide having means
to close the recess, and a face portion nar-
rower than the body thereof projecting out-
wardly from the side face of the jaw, the 90
said projecting part being extended later-
ally to overlap the side face of the other
and opposing vise jaw, when in a closed re-
lation.

In testimony of the foregoing specifica-
tion I do hereby sign the same in the town
of Amenia, county of Dutchess and State of
New York, this 2nd day of March 1915.

WILLIAM J. MAHONEY.
